Inventor

A. N. Kellogg

United States Patent Office.

ANSEL N. KELLOGG, OF CHICAGO, ILLINOIS.

Letters Patent No. 88,180, dated March 23, 1869.

IMPROVEMENT IN BLOCKS FOR HOLDING STEREOTYPE-PLATES.

The Schedule referred to in these Letters Patent and making part of the same.

To all whom it may concern:

Be it known that I, ANSEL N. KELLOGG, of Chicago, in the county of Cook, and State of Illinois, have invented a new and useful Improvement in Blocks for Holding Stereotype-Plates; and I do hereby declare and make known that the following is a full, clear, and exact description thereof, reference being had to the accompanying drawings, and the letters and figures marked thereon, which form part of this specification.

My said invention relates to an improvement in the construction of the blocks upon which removable stereotype or electrotype-plates are secured for the purpose of permitting a change of the printing-forms, as desired; and

Said invention consists in the application of a spring to said block, in such a manner that it operates, in connection with a dovetailed groove, or its equivalent, to hold the plates in place securely, while, at the same time, the plates may be readily removed when desired, as hereinafter more fully set forth.

To enable those skilled in the art to understand how to construct and use my said invention, or improvement, I will proceed to describe the same with particularity, making reference, in so doing, to the aforesaid drawings, in which—

Figure 1 represents an end view of my said invention;

Figure 2 is a side view of the same; and

Figure 3 is a central vertical longitudinal section thereof.

Similar letters of reference in the several figures, denote the same parts of my invention.

A represents the removable plate, and B, the block upon or to which said plate is secured.

There is formed upon the top of said block B, a longitudinal groove, extending from one end nearly to the other end of said block; said groove being provided with re-entrant sides, or points, as shown at b b, in fig. 1, forming a dovetailed way, or groove, in which the plate A, provided with the corresponding outward points, or projections e e, may slide longitudinally, and be held firmly in place so far as a vertical movement, or a longitudinal movement in the direction toward the lip or wall l, is concerned.

Within or below the bottom of the dovetailed groove aforesaid, is a longitudinal recess, marked a, in which is arranged a spring, c, its end being secured to the block, by means of a rivet-bolt, or pin C, or in any other suitable manner.

The recess a permits the spring c, when depressed, to lie wholly beneath the bottom of the aforesaid dovetailed groove, as also the vertical lip d, upon its projecting end; and when said spring is thus depressed, the plate A can readily be inserted or withdrawn; but when the plate is in place, the lip d, upon the spring c, passes up against the end of the plate A, so as to secure it effectually against any longitudinal displacement.

Instead of having the lip d pass up at the end of the plate, as shown, said lip may enter a suitable recess in the under side of the plate, to effect the same purpose, in which case it would secure the plate from longitudinal displacement in either direction, thus rendering the lip, or flange l, unnecessary.

Or a spring may be arranged in a vertical recess, D, operating to throw a stop, d, into a suitable recess in the lower side of the plate, which stop can be withdrawn in any suitable manner, when desired; or the configuration of the recess in the plate may be such that the stop would enter the recess when the plate was passed in the groove, while, by having the lip l at the heel of the block made movable, the plate could, by removing or depressing said lip l, be pushed out in the opposite end from that at which it was inserted; or said spring may be arranged in any other suitable manner to operate upon the plate, and prevent any longitudinal displacement, the dovetailed groove aforesaid, and said spring, combined, having the effect to retain the plate firmly in place, both as to vertical, lateral, and longitudinal movements, as desired.

The ordinary mode of securing the removable plates is by means of screws passing through the face of the plates, both defacing and injuring the plates, and being much more inconvenient and difficult in the changing of the plates.

Having described the nature, construction, and operation of my said invention, I will specify what I claim, and desire to secure by Letters Patent.

I claim the combination of a spring, c, with the block B, when constructed with a longitudinal dovetailed groove, or bed, and the removable plate A, when provided with rebated sides e e, all arranged to operate substantially as and for the purposes herein shown and set forth.

A. N. KELLOGG.
